EX

OR D 19•330

DESIGN.

—o—
H. HACKL.

CURTAIN OR COVER.

No. 19,330.

Patented Oct. 1, 1889.

UNITED STATES PATENT OFFICE.

HEINRICH HACKL, OF VIENNA, AUSTRIA-HUNGARY, ASSIGNOR TO MILLS & GIBB, OF NEW YORK, N. Y.

DESIGN FOR A CURTAIN OR COVER.

SPECIFICATION forming part of Design No. 19,330, dated October 1, 1889.

Application filed August 14, 1889. Serial No. 320,758. Term of patent 3½ years.

To all whom it may concern:

Be it known that I, HEINRICH HACKL, of Vienna, Austria-Hungary, have invented a new and original Design for Curtains or Covers, of which the following is a specification, reference being had to the accompanying photograph, forming a part thereof.

The leading features of the design consist of a panel A, constituting the side and end borders, composed of a series of rustic figures a, shaped as at figure a', each of the figures a being apparently connected. A fancy narrow border B is drawn upon the field B', surrounded by the panel A, the sides of the border being straight, the upper end cap-shaped, as shown at b, and the lower end irregular, as shown at b'. Within the border B, near the cap-like end, pendent figures d are drawn upon the field B', and above the cap-like end of the border B a transverse panel d' is drawn, and lattice-work figures d² are drawn upon

the space intervening the transverse panel d' and the said cap-like end of the border B.

Upon the field B', within the border B, at the irregular end thereof, a series of pedestal-like figures d³ is drawn, the outer figures extending above the center figure. Between the end section of the panel A and the irregular end of the border B, near the former, a transverse panel d¹ is made, and a series of 30 star-like figures d⁵ and banner-like figures d⁶ are drawn upon the field located between the irregular end of the border B and the lower rectangular panel d⁴.

I claim—

A design for a curtain or cover, substantially as herein shown and described.

HEINRICH HACKL.
